WILLIAM A. TRAVER, OF PROVIDENCE, RHODE ISLAND, ASSIGNOR TO FRANKLIN PROCESS COMPANY, OF PROVIDENCE, RHODE ISLAND, A CORPORATION OF RHODE ISLAND.

DYEING APPARATUS.

1,200,546.

Specification of Letters Patent. Patented Oct. 10, 1916.

Application filed February 18, 1916. Serial No. 79,204.

To all whom it may concern:

Be it known that I, WILLIAM A. TRAVER, a citizen of the United States, residing at Providence, in the county of Providence, 5 State of Rhode Island, have invented certain new and useful Improvements in Dyeing Apparatus, of which the following is a specification.

My invention relates to improvements in 10 dyeing-apparatus for use in dyeing or similarly treating yarn and other textile materials wound into the form of cops or packages.

The object of my improvement is to provide 15 means for holding the yarn-cops or packages under compression on the perforated tubes or standpipes on which they are treated, while allowing for their convenient application thereto and ready removal therefrom.

With this object in view my invention consists essentially of an improved flange or head adapted to be applied to the end of the standpipe to bear against the series of 25 cops arranged thereon, and provided with means for securing it in place at different points therealong, while adapting it to be easily disconnected to allow for the removal of the cops after the completion of the 30 dyeing process.

The manner and means for carrying out my improvements are fully described in the following specification, illustrated by the accompanying drawings, in which like reference characters designate like parts.

In the drawings:—Figure 1 is a plan view of my improved end-flange or head showing the means for detachably securing it to the standpipe; Fig. 2, a vertical, sectional view 40 of the device, taken on the line X—X of Fig. 1, illustrating a portion of the standpipe with the yarn-cops assembled thereon; and Fig. 3, an enlarged detail view in perspective of the spring-washer which operates with the fastening-means for the flange to frictionally hold it in place.

My invention is adapted for use particularly with the system of dyeing or treating yarns known as the "Franklin" process 50 as described in U. S. Letters Patent No. 996,761, granted to J. C. Hebden and F. H. Daniell July 4, 1911. According to this method the yarn is wound into cylindrical cops or packages which are capable of being 55 axially contracted under pressure and are

placed end-to-end on a perforated pipe through which the dye-liquor is circulated. Before being treated with the dyeing bath the yarn in the several cops is subjected to compression to bring all of its parts to a 60 uniform density and this is accomplished by placing heads or flanges against the end cops of the series and forcing them toward each other along the standpipe. After the cops have thus been compressed the flanges 65 are secured in place to maintain the yarn under compression during the dyeing process.

Referring to the drawings, in Fig. 2 P designates the upper end of the standpipe 70 or stringer on which the yarn cops C, C are assembled and F is the end-flange for compressing them longitudinally thereof. Fitted to the end of the bore of the pipe P is a cylindrical plug E which forms an 75 extension or continuation of the pipe, on which the flange F is adapted to slide. The plug or extension E is held in place by a cross-pin p or any other suitable means and serves as a closure for the end of the pipe P, besides acting as a support for the 80 flange F. Usually the flange F is circular in shape, provided at its center with a bore f to receive the extension E of the pipe P and formed on its top with a raised lug 85 or cross-rib f'. Adapted to slide on the top of the rib f' is a plate or slide S formed with two alining! spaced slots s, s through which extend screws s', s' screwed into the flange F. Underlying the heads of the 90 screws s', s' and bearing against the top of the slide S are suitable spring-washers w, w preferably constructed of a helical coil of flat wire as shown in the enlarged view, 95 Fig. 3. The pressure of the washers w applies a slight, frictional resistance to the sliding movement of the slide S to maintain it in its adjusted position against accidental displacement as hereinafter more fully explained. At one end the slide S is formed with an upwardly bent rib or extension s² 100 which serves as a means for grasping it with the fingers to slide it back and forth on the flange F.

Referring to Fig. 2, the extension E of the pipe P is formed with a series of annular grooves g, g, etc., spaced a slight distance apart along its length and adapted to receive the sides of an opening o in the slide S. As shown in Fig. 1 the opening o is 105 110

shaped somewhat like a buttonhole having an enlarged portion σ' adapted to the outside diameter of the extension E and a smaller portion σ^2 fitted to the reduced diameter of the grooves g . When the slide S is drawn out to the left, as shown by dash lines in Fig. 1, the enlarged portion σ' of its opening σ will come into register with the central opening f of the flange F so that the latter can be slipped onto the extension E. Preferably the slots s in the slide S are so proportioned that their ends strike against the screws s' and act as a stop to prevent further movement of the slide after its enlarged opening has been brought opposite the opening f in the flange F. On the bottom of the flange F is a circular rib or rim f^2 surrounding the opening f and tapered downwardly on its outside. The purpose of the rim f^2 will be explained in connection with the method of operation of the whole device which is as follows: In employing the system of dyeing hereinbefore referred to the yarn is first prepared for the immersion process by winding it on porous tubes which are contractible along their length. The type of tube usually adopted is shown in Fig. 2, and consists of a helical coil of spring-wire T covered by a flexible sleeve B of porous fabric or other foraminous material such as stockinet. The ends of the sleeves B project a slight distance beyond the ends of the coils T and when the cops C are strung on the standpipe P are usually folded or doubled into the center of the tube to dispose them out of the way. Heretofore, however, considerable difficulty has been experienced from the projecting portion of the sleeve B of the end-cop which frequently interferes with the end-flange and prevents it from setting down tightly against the yarn. That is to say, the extra length of sleeve projecting outwardly beyond the end of the cop is liable to bunch up and interfere with the placing of the flange on the standpipe so that a fluid-tight joint cannot be effected. To guard against this trouble I have provided the tapered rim or boss f^2 around the flange-opening f which acts automatically to force the end of the sleeve B into the opening in the cop to dispose it out of the way and prevent it from interfering with the placing of the flange.

It is the usual practice to employ a series of standpipes P in the interior of the leir in which the yarn is dyed and generally they are permanently fixed in position projecting upwardly from a false-bottom. Usually the standpipes have permanent flanges fixed to their lower ends and only the upper ones are removable, although the arrangement may be varied if desired to adapt both flanges for detachment. For instance, it has heretofore been proposed to dye yarn in the

form of a single package wound in the manner of a warp-spool and for this purpose the standpipes or stringers are removable from the leir and have both of their end-flanges detachable as a matter of convenience in handling. It is obvious that my improved attaching-means for the flange is adaptable for this latter arrangement, but for the sake of simplicity in describing it I have here shown the device as applied to one flange only.

After the cops C have been assembled end-to-end on the standpipe P the flange F is applied thereto as follows: The slide S is first drawn to the left as illustrated by the dash-lines in Fig. 1, and when the ends of the slots s bring up against the screws s' the enlarged opening σ' will register with the central opening f of the flange. The flange F is then slipped onto the end of the extension E of the standpipe P and pressed down against the end-cop C to compress all of the packages lengthwise of their axes and bring the masses of yarn therein to a uniform density. As the flange F is forced down against the end-cop C the tapered boss f^2 surrounding its opening f will push the end of the fabric tube B into the cop to guard against its obstructing the sealed joint between the face of the flange and the yarn. The flange F is forced down against the yarn until its slide S comes into alignment with one of the peripheral grooves g on the extension E and the slide S is then slid across its boss f^2 to engage the sides of its contracted opening σ^2 with the groove g as shown by dotted lines in Fig. 1. Through this engagement the flange F is secured against longitudinal displacement on the standpipe P to hold the yarn-cops under compression. As before explained, the spring-washers w retain the slide S in its adjusted position against accidental displacement, and when it is required to remove the flange F it is only necessary to again withdraw the slide to the left as first explained.

It is obvious that instead of providing the longitudinal extension E at the end of the pipe P, the pipe itself might be scored with the grooves g for the engagement thereof with the slide S on the flange F. Likewise, the grooves g might be cut on opposite sides of the standpipes instead of circumferentially therearound, or raised ribs or projecting pins could be used in their stead for overlapping and engaging the top of the slide. Various other modifications might also be made in the construction and arrangement of the device without departing from the spirit and scope of the invention.

Therefore, without limiting myself to the exact embodiment shown, what I claim is:

1. In a dyeing-apparatus, the combination with a tubular perforated stringer adapted to

receive a plurality of dye-cops strung along its length and having an imperforate portion at one end, of a flange fitted to slide on the stringer to compress the yarn in the cops, and means adjustable laterally across the flange to engage the imperforate portion of the stringer at different distances from its end to secure the flange in place thereon.

2. In a dyeing-apparatus, the combination 10 with a hollow perforated stringer adapted to hold a plurality of dye-cops strung along its length and formed with an imperforate section at its end, of a flange having an opening for receiving the end of the stringer 15 to adapt its slide thereon, and manually-operable means movable laterally on the flange to engage the imperforate portion of the stringer to secure the flange in position thereon.

20 3. In a dyeing-apparatus, the combination with a stringer adapted to hold a plurality of dye-cops strung along its length and formed at its end with a series of spaced-apart grooves, of a flange fitted to slide on the stringer, and manually-operable means on the flange for individually engaging the grooves of the stringer to secure the flange in different positions thereon.

4. In a dyeing-apparatus, the combination 30 with a stringer for holding a series of dye-cops strung along its length, said stringer formed at its end with spaced-apart grooves, of a flange formed with an opening to receive the stringer to adapt it to slide thereon, 35 and a member slidable laterally of the flange and formed to embrace the stringer to engage with its grooves to secure the flange in different positions thereon.

5. In a dyeing-apparatus, the combination 40 with a stringer adapted for holding a series of dye-cops and formed at one end with spaced-apart peripheral grooves, of a flange fitted to slide on the stringer, and a plate mounted on the flange to slide laterally 45 thereof and formed with an opening arranged to admit the stringer in one position and to engage the grooves thereof in the opposite position to secure the flange in place thereon.

6. In a dyeing-apparatus, the combination 50 with a stringer adapted for holding a series of dye-cops and formed at one end with spaced-apart peripheral grooves, of a flange formed with a central opening to adapt it to slide on the stringer, and a plate formed 55 with a button-hole opening enlarged at one end to adapt it to register with the central opening of the flange and contracted at the opposite end to adapt its sides to engage with the grooves on the stringer. 60

7. In a dyeing-apparatus, the combination with a stringer adapted to hold a series of dye-cops strung thereon and formed with spaced-apart grooves on its periphery, of a flange fitted to slide on the stringer, a securing-member formed with an opening 65 enclosing the stringer and slideable on the flange to engage the sides of the opening with the grooves thereof, and resilient-means engaging said member to resist its 70 sliding movement to retain it in its adjusted position.

8. In a dyeing-apparatus, the combination with a stringer adapted to support a series of dye-cops strung thereon, of a flange 75 formed with a central opening fitted to the stringer to adapt the flange to slide thereon and provided with a tapering boss surrounding the opening on its under side to adapt it to project within the opening of the dye-cop 80 to force the projecting end of its tube therein, and means adjustable on the flange for engaging the stringer at varying distances from its end to secure the flange in different positions thereon. 85

9. In a dyeing apparatus, the combination with a tubular stringer for supporting a series of dye-cops strung thereon, of a cylindrical plug secured in the end of the stringer and projecting therefrom with its 90 periphery scored with spaced-apart grooves, a flange having a central opening fitted to the stringer to adapt it to slide therealong, and a slide adjustable laterally of the flange 95 to engage it with the grooves of the stringer to secure the flange in place thereon.

In testimony whereof I affix my signature.

WILLIAM A. TRAVER.
